UNITED STATES PATENT OFFICE.

JOHN WILLIAM SCHULZE, OF PROVIDENCE, RHODE ISLAND, ASSIGNOR TO ALFRED VESTER SONS, INC., OF PROVIDENCE, RHODE ISLAND, A CORPORATION OF RHODE ISLAND.

DESIGN FOR A PENDULET.

60,883.

Specification for Design.

Patented Apr. 18, 1922.

Application filed September 23, 1921. Serial No. 502,840. Term of patent 3½ years.

To all whom it may concern:

Be it known that I, JOHN WILLIAM SCHULZE, a citizen of the United States, residing at Providence, in the county of Providence and State of Rhode Island, have invented a new, original, and ornamental Design for a Pendulet, of which the following is a specification; reference being had

to the accompanying drawing, forming part thereof.

The figure is a perspective view of a pendulet, showing my new design.

I claim:

The ornamental design for a pendulet, as shown.

JOHN WILLIAM SCHULZE.
